UNITED STATES PATENT OFFICE.

THOMAS D. HOXSEY, OF PATERSON, NEW JERSEY.

TAPE FOR SPRING-SKIRTS.

Specification forming part of Letters Patent No. 31,388, dated February 12, 1861; Reissued April 19, 1864, No. 1,655.

To all whom it may concern:

Be it known that I, THOMAS D. HOXSEY, of the city of Paterson, New Jersey, have invented a new and valuable Improvement 5 or Combination in Making Tapes for the Manufacture of Hoop or Spring Skirts; and I do hereby declare the following is a full and exact description thereof reference being had to the accompanying drawings, with 10 the letters of reference marked thereon.

My invention or combination consists in weaving a sack or bag running lengthwise through the tape in combination with the ordinary rectangular sack or bag now generally used in making tapes for hoop or 15 spring skirts. The object of such longitudinal tube or bag being for the reception of a spring running lengthwise through the bag of the tape, so that when manufactured 20 into skirts such longitudinal spring shall answer the purpose of reextending the skirt after it may have been collapsed or brought together by sitting or otherwise.

By reference to the accompanying drawing 25 ing the letter A, represents the tape.

B represents the longitudinal bag running lengthwise through the tape with the spring. P represents the rectangular pocket or bag of said tape.

I disclaim any right to use a spiral metallic spring for the purpose aforesaid. I also disclaim any right to a patent for the mere manner of weaving the said tape.

What I claim as my invention and desire to secure by Letters Patent is—

The combination of the longitudinal sack B running lengthwise through the tape with the rectangular bag or pocket now in use for the purpose of receiving a spring in such longitudinal sack or bag, in order to re- 40 extend the skirt after the same may have been collapsed by sitting or otherwise.

Dated at Paterson, New Jersey, December first, eighteen hundred and sixty.

THOS. D. HOXSEY.
